Patented Jan. 18, 1921.

UNITED STATES PATENT OFFICE.

JORGENSEN, OF CRAIG, NEBRASKA.

PUMP-JACK.

1,365,785.

Specification of Letters Patent. Patented Jan. 18, 1921.

Application filed February 16, 1920. Serial No. 359,210.

To all whom it may concern:

Be it known that I, JORGENSEN, a citizen of the United States, residing at Craig, in the county of Burt and State of Nebraska, have invented certain new and useful Improvements in Pump-Jacks, of which the following is a specification.

This invention relates to an improvement in pump jacks, and has for its object to provide such a construction that power may be applied conveniently and effectively for pumping water or other liquids, and which will require few and simple parts so that durability may be attained and manufacture will be economical.

The invention consists of the novel construction, combination and arrangement of parts as described herein and claimed, and as illustrated in the accompanying drawing, wherein,—

Figure 1 is a view in side elevation of a pump jack embodying my invention. Fig. 2 is a plan view of the same. Figs. 3 and 4 are enlarged details to clearly show the mounting of the rollers in the apertures of the rock-levers. Fig. 3 is a sectional view on line 3—3 of Fig. 4. Fig. 4 is a sectional view on line 4—4 of Fig. 3. Fig. 5 is a sectional view on line 5—5 of Fig. 1, the scale being enlarged.

In the drawing, numeral 6 indicates a pump-rod adapted to be reciprocated for elevating a liquid to be discharged from the pump 7 by actuation of a rotatable pulley 8, said pulley being mounted to rotate with the shaft 9.

I provide a casting having a part 10 formed as a receptacle in which is disposed a gear wheel 11 and a pinion 12 in engagement with said gear wheel, said receptacle also being adapted to contain a lubricating oil, said casting including a pair of legs 13 having flanges 14 adapted to be secured to a support 15.

Numerals 16 indicate a pair of curved arms adapted to be pivotally connected with the pump-rod. At 17 is indicated a shaft for the gear-wheel 11, said shaft having bearings in the side walls of the receptacle 10, upon the outer ends of said shaft being mounted a pair of adjusting-disks 18.

Each disk 18 is provided with a plurality of apertures α , and certain of these apertures are disposed nearer to the peripheries of the disks than others, as best shown in Fig. 1. I provide a pair of rollers

or wheels 19, each being mounted upon a wrist-pin 20, the inner end of each wrist-pin being adapted to be mounted in an aperture α of a disk.

Numerals 21 indicate a pair of rock-levers, each being fulcrumed upon an arm 22 which projects horizontally from the upright casting, the inner ends of said levers 21 being provided with elongated apertures α for receiving the rollers 19, the outer ends of said levers being pivotally connected with the curved arms 16, as indicated at b , said rollers preferably being provided with flanges c for engaging the sides of the rock-levers adjacent to the apertures α .

As best shown in Fig. 5, the casting is provided with a sleeve d which projects outwardly from one of its sides to provide bearings for an idler pulley, useful in instances when it is desired to shift a belt (not shown) from the pulley 8 thereto, this being of advantage when "starting" an engine.

Having described the several parts, operation will be readily understood. When the pulley 8 is rotated the pulley 12 will be actuated for rotating the gear wheel 11, which causes a revoluble movement of the disks 18 for actuation of the rock-levers 21 to reciprocate the pump-rod 6, a long stroke for the pump-rod being effected by mounting the pins 20 in the apertures α of the disks, farthest from the centers of said disks, said pump-rod as is obvious, having a comparatively short stroke when the pins 20 are disposed in the apertures α nearer to the centers of said disks, this being of great advantage, depending upon the depth of wells and height to which water is to be pumped, and upon the degree of power employed for operation.

Having fully described my invention, what I claim and desire to secure by Letters Patent is,—

1. In a pump jack, the combination of a pump-rod provided with arms, a container, shafts provided with gear wheels and journaled in the walls of the container, disks provided with apertures at varying distances from their axes and mounted on one of said shafts, a pair of rock-levers fulcrumed on the receptacle and pivotally connected with the arms of the pump-rod, a pair of wrist-pins each provided with a roller member and mounted in an aperture of a disk, each rock-lever being provided with an elongated aperture for receiving a roller-member.

2. In a pump-jack, the combination of a pump-rod provided with arms, a casting provided with legs and having a part formed as a container, a revolute shaft
5 journaled in the walls of the container, disks provided with apertures at varying distances from their axes and mounted on said shaft, apertured rock-levers fulcrumed on the casting and pivotally connected with
10 the arms of the pump-rod, a pair of wrist-

pins each being mounted in an aperture of a disk, and a pair of rollers each being mounted on a wrist-pin and engaging in an aperture of a rock-lever.

In testimony whereof I have affixed my 15
signature in presence of two witnesses.

JORGENSEN.
